OVERFLOW DEVICE FOR LIQUID CONTAINERS

Malcolm D. Riker, Detroit, Mich.

Application November 13, 1943, Serial No. 510,223

4 Claims. (Cl. 4—206)

1

This invention relates to overflow devices for liquid containers, the principal object being to provide a means associated with the container whereby a desired depth of liquid may be maintained therein under a constant flow of liquid thereto.

The particular function of the device is to discharge the liquid from the surface of the body thereof in the container to the outlet and by use of the device in a bath tub the scum which accumulates on the surface of the water within a bath tub is, in my improved apparatus, constantly being discharged to the outlet and thus, with the inlet valve open to provide a desired volume of flow per unit of time thereinto, a constant level of liquid is maintained in the tub.

While I have shown a bath tub in the drawing, my improved overflow device would readily function with other types of containers wherein the floating matter that may be introduced with fluid into the container is constantly discharged to the outlet.

These and other features and objects of the invention are hereinafter more fully described and claimed and shown in preferred form in the accompanying drawing in which—

Fig. 1 is a sectional elevation of the discharge end of a container such as a bath tub showing my improved overflow device.

Fig. 2 is a plan view thereof.

Fig. 3 is a vertical section of a portion of the container showing an alternative form of the overflow means.

Fig. 4 is a plan view of the form of the overflow means shown in Fig. 3.

Fig. 5 is an enlarged cross section taken on line 5—5 of Fig. 3.

In many liquid containers wherein material in a fluid form containing floating particles is discharged or in containers such as bath tubs wherein a scum tends to accumulate on the surface of the liquid, it is desirable in either case to provide for a constant discharge of the contaminated liquid accumulating at the surface of the liquid in the container.

In the form of the invention shown in Fig. 1 the container 1 has the usual outlet 2 adjacent the top at one end of the container and the outlet as indicated at 3 in the bottom of the tub or container. With liquid flowing into the tub from an inlet not here shown the tub could fill to the outlet indicated at 2. In order to maintain the liquid level below the outlet and in order that foreign material rising to the surface of the liquid may be discharged I provide means for maintain-

2

ing a variable level of liquid below the usual outlet. Thus in a bath tub, for instance, with a constant inflow of water I provide means for a constant overflow below the level of the usual outlet indicated at 2. The device consists of a flexible shield 4, which may be formed of rubber or other flexible material, as for use in a bath tub, having a peripheral flange 5 thereabout and longitudinal ribs 6 on the outer face of the body to contact the end surface of the tub adjacent the outlet.

The ribs 6 and flange 5 provide channels open at the upper end to the interior of the tub. The flange 5 extends along the two edges and the lower end of the device, as indicated in Figs. 1 and 2, and the lower horizontal portion of the body of the device closes the outlet to the body so that the only liquid that can flow to the outlet is liquid that overflows the upper end of the shield into the space between the body 4 and the inner surface of the tub or container.

Thus, with water flowing into the tub during the time a person is bathing, the scum or dirt that rises to the surface of the liquid is being constantly discharged to the outlet and a constant level of practically clear liquid is maintained in the tub.

The outlet fitting, indicated at 3 in Fig. 1 and at 3a in Fig. 3, may be of any desired form as this invention is not confined to the form of the usual bath tub outlet fitting or the similar fittings of other liquid containers in which, during its use, a constant supply of liquid containing a material that would float to the surface is required to be discharged while maintaining a constant level in the container.

The shield 4 including the integral ribs 6 is preferably formed of rubber, or other flexible material of the same structural features may be employed. Thus the shield may be varied in position as indicated by dotted lines a and a' to provide for a greater or lesser height of liquid to be maintained in the body of the container or tub.

In the alternative form of the invention found in Figs. 3, 4 and 5 the tub or receptacle 1a has an outlet 3a which extends into and its lower ends spaced from an enclosing fitting 9 to which the outlet conduit 10 is connected. It is not material however to this invention what specific structural form of outlet is utilized. It is desirable, however, in the structure shown in Fig. 2 that a cap member 11 be provided spaced from the bottom of the recess 12 to sustain the flexible shield 13 from being forced into closing relationship with the outlet member or conduit 3a.

The shield 13 in the form of the invention

shown in Fig. 3 is a flat piece of material of flexible character while the end of the body of the container is provided with ribs 7 which spaces the vertical face of the shield from contact with the wall 14 of the container. Thus the same function is secured in that a space or a series of spaces may be provided between the shield and the wall 14 of the container, as indicated at 13a in Fig. 5, through which water may overflow to the outlet. The member 13a of Fig. 3 may be varied in position after the manner suggested in the form shown in Fig. 1 to vary the depth of liquid in the bath tub or other container.

While I have shown the shield or wall of the container as having a series of grooves providing for flow of liquid from the surface thereof in the container to the outlet, it is pointed out that the contacting surface of one or the other of the elements may be shaped to provide a single groove of the desired cross sectional area and while I have described a flexible shield the invention is not confined to a shield having flexibility. In either case the hydrostatic pressure of the liquid in the container maintains the shield in position. It is further to be understood that the groove or grooves preferably have a cross sectional area greater than that of the inlet.

Either form of the invention serves the same purposes; that is to provide for a continuous flow of water or liquid from the surface thereof in a container by reason of the continued flow of liquid thereto.

The invention is thus serviceable in many instances to not only maintain a desired level of liquid in a container but to cause a continued flow of liquid from the surface of the body thereof to the outlet. By this arrangement the liquid remaining in the body of the tub or container is in a practically pure state during the use of the device irrespective of the fact that extraneous material of less specific gravity may be introduced into the liquid body during its use.

From the foregoing description it is believed evident that the features and objects of the invention are attained by the structural arrangement and relationship of the various parts and that various changes may be made therein without departing from the spirit and scope of the invention as set forth in the appended claims.

Having thus fully described my invention, its utility and mode of operation, what I claim and desire to secure by Letters Patent of the United States is:

1. An overflow device for a bath tub or other liquid container having a main outlet in its bottom adjacent one wall thereof and an overflow outlet in the said wall adjacent the top, comprising a flexible shield formed of a comparatively flat sheet of material provided with parallel ribs on one surface thereof and providing, when the parts are in position, passageways for liquid open at the upper end to receive liquid and at the bot-

tom to discharge to the tub outlet, the arrangement permitting adjustment of the shield to vary the height of the open end of the passageways from the bottom of the tub, thereby providing for continual flow of liquid to the tub from the inlet without materially varying the level of the liquid in the tub.

2. An overflow device for a liquid container having side and end walls and a bottom having an outlet, comprising a flexible rubber shield having a series of parallel ribs on one surface thereof providing a means for spacing the body of the shield from a wall and the bottom of the container adjacent the outlet, said ribs providing passageways open to the interior of the container at one end only and to the outlet, the flexibility of the shield permitting the same to be adjusted in position longitudinally of the bottom and end wall of the container to vary the height of the open end of the passageway from the bottom of the container and otherwise prevent flow of liquid from the container to the outlet.

3. An overflow device for a liquid container having side and end walls and a bottom having an outlet, comprising a shield formed of a flat sheet of material having a passageway open at one end to receive liquid from the surface of the body thereof in the container and at the opposite end opening to the outlet, the shield being flexible permitting manual movement thereof along a wall of the body and bottom thereof about the outlet to thereby vary the position of the upper end of the shield relative to the bottom of the container, and being maintained in adjusted position by the hydrostatic pressure of the liquid in the container.

4. An overflow device for a bath tub having a main outlet in its bottom adjacent one end and an overflow outlet in said end adjacent the top, comprising a comparatively thin flexible shield of a desired width positionable in the tub to seal the outlet in the bottom of the tub and to extend upwardly along said end of the tub and movable to vary the height of the upper end of the shield above the tub bottom, the surface of one of the members facing the other having parallel ribs spacing the shield from both the said end and bottom of the tub and providing a series of parallel passageways open at the upper end of the shield providing for flow of liquid from the tub to the outlet, the flexibility of the shield permitting variation in the position of the upper end thereof relative to the bottom of the tub and permitting longitudinal movement thereof along the end wall and bottom of the tub to position the upper open end of the passageways at the desired height above the tub bottom to thereby provide for a predetermined liquid level in the tub and permitting a continual flow of liquid to the tube without material variation in the level of the liquid therein.

MALCOLM D. RIKER.
